DANCING FIGURE TOY

Sidney A. Tarrson, 777 S. Tripp,
Chicago, Ill. 60624

Filed May 5, 1969, Ser. No. 17,012

Term of patent 14 years

Int. Cl. D21—02

U.S. Cl. D34—15

FIG. 1 is a perspective view of a dancing figure toy, showing my new design;

FIG. 2 is a side elevational view thereof, the opposite side being substantially the same;

FIG. 3 is a rear elevational view thereof;

FIG. 4 is a bottom plan view thereof.

I claim:

The ornamental design for a dancing figure toy, as shown and described.
